Attorney.

UNITED STATES PATENT OFFICE.

TAMIS CORNELIS SCHENK, OF AMSTERDAM, NETHERLANDS, ASSIGNOR TO JOHANNES WILHELMUS ALBERTUS DE WILD, OF ROTTERDAM, NETHERLANDS.

CLAMPING DEVICE FOR THE CONNECTION OF POLES, BALKS, AND THE LIKE.

1,269,964.

Specification of Letters Patent. Patented June 18, 1918.

Application filed October 18, 1916. Serial No. 126,400.

To all whom it may concern:

Be it known that I, TAMIS CORNELIS SCHENK, a subject of the Queen of the Netherlands, residing at No. 93 van Woustraat, 5 Amsterdam, the Netherlands, have invented certain new and useful Improvements in Clamping Devices for the Connection of Poles, Balks, and the like, of which the following is a specification.

10 This invention relates to a device with the aid of which poles, balks and the like of a particular thickness can be quickly and readily connected and which device can be used repeatedly.

15 A preferred embodiment of the invention is illustrated in the accompanying drawings, in which:

20 Figure 1 is a side elevation of two balks connected to each other by means of clamping devices according to the invention.

Fig. 2 is a cross section through the line A—A in Fig. 1; viewed in the direction of the arrows to said line.

25 Fig. 3 is a side elevation of two balks with the clamping device applied in a position ready for being tightened or just after having been untightened.

30 The clamp 1 is at its extremities provided with hooks 2 in which a locking piece 3 of flat iron can be inserted. At a distance from said hooks 2 equal to the width of the flat iron bar 3, i. e. at the places indicated by 4, the legs of the clamp are bent up. In the position shown in Fig. 1 the points 5 and 35 6 of the locking piece and the point 7 of the clamp are situated on a broken line. The locking piece 3 and the clamp 1 form with the balks a knee lever, which is in steady balance, the edge 6 of the locking piece resting in the angle 4 of the legs of said clamp. Under extraordinarily heavy loads the balks 8 and 9 might slide along each other

in the lengthwise direction across a little distance, in which case the knee lever would be tightened stronger and the pressure between the balks would be increased. Experiments have proved, however, that by means of the knee lever the balks are pressed against each other so tight that at normal loads no sliding in a perceptible degree takes place.

When applying the clamps the points 6' and 7. (Fig. 3) are placed exactly opposite each other, in other words in a plane perpendicular to the direction of the balks. 45 The knee lever 5', 6', 7 can be pressed through its dead point, thereby assuming the position shown in Fig. 1. In order to enable this to be done by hand a spanner or similar tool may be placed on the locking piece 3, 50 so that the same can be turned with great force.

Having now described my invention, what I claim and desire to secure by Letters Patent is:

65 A clamping device for connecting poles and balks comprising a U-shaped clamp, obliquely extending legs on said clamp extending beyond the poles, hook-shaped portions at the end of said legs and a locking 70 piece inserted in said hook-shaped portions with one edge thereof bearing against the outer pole so that said locking piece can turn on said edge into locking position against the obliquely extending legs of the 75 clamp when the latter is turned about its contact edge with the inner pole.

In testimony whereof I affix my signature in presence of two witnesses.

TAMIS CORNELIS SCHENK.

Witnesses:

J. W. A. DE WILD,
H. J. Kou.
